UNITED STATES PATENT OFFICE.

JOHN KAROLY, OF CHICAGO, ILLINOIS.

TAMPERING-PREVENTING DEVICE FOR FIRE-ALARM BOXES.

1,149,199.

Specification of Letters Patent. Patented Aug. 10, 1915.

Application filed April 5, 1915. Serial No. 19,420.

To all whom it may concern:

Be it known that I, JOHN KAROLY, a subject of the King of Hungary, residing at Chicago, in the county of Cook and State of Illinois, have invented certain new and useful Improvements in Tampering-Preventing Devices for Fire-Alarm Boxes, of which the following is a specification.

This invention relates to certain new and useful improvements in tampering preventing device for fire alarm boxes.

The primary object of the invention is to provide a hand-retaining device in connection with a fire alarm box, and whereby the hand of the person who is manipulating the alarm mechanism is grasped and retained until the officers of the fire department arrive and actuate the releasing mechanism.

The present invention is designed primarily to prevent tampering with fire alarm boxes and to prevent false alarms from being turned, the mechanism being arranged so as to hold the operator of the alarm system until a fire department officer arrives and the box being provided with such an attachment would render unfounded alarms impracticable.

A still further object is to provide the fire alarm boxes of a city fire department with locking means engaging the wrist of a person who operates the alarm box, thus holding said person at the box until the fire department officer arrives and ascertains the location of the fire, or in the event that a false alarm has been turned in, an arrest is made of the person tampering with the alarm.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views, Figure 1 is a vertical sectional view taken through the device upon line I—I of Fig. 2 showing the elements in their normal set positions. Fig. 2 is a sectional view taken upon line II—II of Fig. 1. Fig. 3 is a horizontal sectional view taken upon line III—III of Fig. 1, and Fig. 4 is an enlarged detail sectional view

of one of the locking members in its sprung or arm-engaging position.

Referring more in detail to the drawings, a hollow casing 10 is provided for completely inclosing the fire alarm box 11, the casing box being mounted upon a permanent support wherever desired such as being secured to a post of a building. The forward side 12 of the casing has a cylindrical sleeve 13 horizontally arranged therethrough, and being of sufficient size to accommodate the arm of a man and to allow a person to insert his hand therethrough into the casing 10 for the purpose of turning the key or switch 14 of the alarm box and thereby turning in the alarm.

Arm-engaging feet 15 are provided upon the inner ends or bars 16 which are longitudinally slidable within spaced brackets 17 and 18 within the casing 10, the said bars and feet being positioned through oppositely arranged peripheral openings 19 in the collar 13. A trip pin 20 is slidably arranged within the bracket 18 and is normally projected through an opening 21 in the bracket by means of a spring 22 carried by the bracket and so as to engage the adjacent face of the bar 16. When the bar 16 is moved outwardly to the limit of its movement, the foot 15 will fit within its respective opening 19, the edges of each foot and opening being inclined to correspond and thus providing an unbroken inner surface for the collar as shown in Figs. 1 and 2. When the bars are so positioned outwardly in their unlocked arrangement, the pins 20 will automatically enter the side notches 23 of the said bars, thus locking the bars in their normal position. A coil spring 24 is secured as at 25 to each of the bars 16, and also to the adjacent brackets 17 as at 26 and whereby as will be evident a releasing of the trip pin 20 from the bar notch 23 allows its respective spring 24 to force the bar feet 15 inwardly to their locking positions.

Each of the brackets 17 are provided with locking pins 27 which are pressed inwardly by means of springs 28 and so as to engage the adjacent face of the bars 16 with the teeth 29 thereof. The operation of the springs 24 thereby move the toothed portions of the bars 16 in a ratcheting movement beneath the pins 27 which pins will prevent any unauthorized retraction of the bars and feet.

100

95

105

110

Each of the trip pins 20 are provided with cords 30 which are attached as at 31 to a pulley 32 mounted upon a turn shaft 33 extending through the casing 10 and having the end thereof opposite the said pulley provided with a ratchet wheel 34 and a sprocket wheel 35.

A dog 36 is carried by the box 11 for engaging the ratchet wheel 34, while a sprocket chain 39 runs over the sprocket wheel 35 and a further sprocket wheel 38 which is carried by the shank 39 of the operating key 14 of the box.

From this detailed description of the invention, the complete operation thereof will be at once apparent. The mechanism is normally arranged as shown in Figs. 1 and 2 and a person desiring to turn in a fire alarm projects his hand and forearm through the collar 13 and turns the key 14 with his hand thereby setting the alarm mechanism in operation. Such action also turns the shaft 33 through the means of the sprocket chain 37 and thus turns the pulley 32 exerting a pull upon all of the cords 30 which are attached to the trip pins 20, thereby releasing all of the said pins and allowing the springs 24 to inwardly project the bars 16 and feet 15 which will thereby forcibly engage the arm of the operator and prevent the removal of his hand from the casing 10. The fire department being advised by means of the system of the location of the alarm box, the proper officer visits the box and may release the person sending in the alarm. The end doors 40 of the casing 10 may then be opened by releasing the locks 41 thereof so that free access will be had to the interior of the casing and the bars 16 may again be retracted for engagement by the trip pins 41, and the entire device reset by the proper turning of the key 14.

While the form of the invention herein shown and described is what is believed to be the preferred embodiment thereof, it is nevertheless to be understood that minor changes may be made without departing from the spirit and scope of the invention as set forth in the claims.

50 What I claim as new is:—

1. An alarm box, an operating key mounted thereon, an inclosing casing for the said box, an arm receiving collar extending through one side of the said box and having radial openings therethrough, radially arranged slidably mounted locking bars carried by the said casing and extending through the said openings, resilient locking pins in engagement with the said bars, trip pins in locking engagement with

the said bars when the latter are in their normal positions, releasing cords between the said trip pins and the said key, and projection springs in operative engagement with the said bars.

65

2. A device of the class described comprising a fire alarm box, a revoluble operating key carried thereby, a sprocket wheel upon the said key, an inclosing casing for the said box, an arm receiving collar extending through one side of the said casing and provided with oppositely-arranged openings within said casing, a turn shaft extending through the said casing and adjacent the said box, a ratchet wheel, a sprocket wheel and a pulley upon the said shaft, a sprocket chain in engagement with the said sprocket wheels, a dog carried by the said box in engagement with the said ratchet wheel, arm engaging means extending through the said collar openings, bars engaging trip pins, and trip cords connected between the said pulley and trip pins.

80

3. A device of the class described comprising a fire alarm box, a revoluble operating key carried thereby, a sprocket wheel upon the said key, an inclosing casing for the said box, an arm receiving collar extending through one side of the casing and provided with oppositely-arranged openings within said casing, a turn shaft extending through the said casing and adjacent the said box, a ratchet wheel, a sprocket wheel and a pulley upon the said shaft, a sprocket chain in engagement with the said sprocket wheels, a dog carried by the said box in engagement with the said ratchet wheel, brackets arranged in pairs within said casing, radially slidable bars mounted within the said brackets having ratchet teeth, and a stop notch in one side thereof and extending through the said collar openings, arm engaging feet upon the inner ends of the said bars, a resiliently mounted locking pin carried by one bracket of each pair in engagement with the said teeth, a projection spring for each of the said bars, spring-pressed trip pins carried by the others of the said brackets in normal engagement with the said bar notches when the bars and feet are in their normal set positions, and releasing cords operatively connected between the said trip pins and pulley.

In testimony whereof I affix my signature in presence of two witnesses.

JOHN KAROLY.
